US00D920772S

(12) **United States Design Patent** (10) **Patent No.:** **US D920,772 S**
McClung (45) **Date of Patent:** **** Jun. 1, 2021**

(54) **CLAMPING ASSEMBLY**

(71) Applicant: **David L. McClung**, Des Moines, IA (US)
(72) Inventor: **David L. McClung**, Des Moines, IA (US)

(**) Term: **15 Years**

(21) Appl. No.: **29/686,407**

(22) Filed: **Apr. 4, 2019**

(51) **LOC (13) Cl.** **08-08**
(52) **U.S. Cl.**

USPC **D8/394; D8/382**

CLAIM

The ornamental design for a clamping assembly, as shown and described.

DESCRIPTION

FIG. 1 is a top right isometric view of a clamping assembly; FIG. 2 is a top right isometric view of a clamping assembly; FIG. 3 is a front elevation view of a clamping assembly; FIG. 4 is a rear elevation view of a clamping assembly; FIG. 5 is a right elevation view of a clamping assembly; FIG. 6 is a left elevation view of a clamping assembly; FIG. 7 is a top plan view of a clamping assembly; and, FIG. 8 is a bottom plan view of a clamping assembly.

A description of the appearance of the article is as follows: The broken lines showing portions of the design in all figures is included for the purpose of illustrating environment and unclaimed features and forms not part of the claimed design.

1 Claim, 5 Drawing Sheets
